HUMIDIFIER

Eugene R. Luedtke, Reedsburg, Wis., assignor to Hanks-craft Company, Reedsburg, Wis., a corporation of Wisconsin

Filed Apr. 16, 1962, Ser. No. 69,730

Term of patent 14 years

(Cl. D62—2)

FIG. 1

FIG. 2

FIG.5

FIG. 1 is a front perspective view of a humidifier embodying my new design;

FIG. 2 is a top plan view thereof;

FIG. 3 is a front elevational view thereof, the rear not shown being substantially the same;

FIG. 4 is a side elevational view thereof, the opposite side not shown being substantially the same; and

FIG. 5 is a bottom plan view thereof.

The conventional electric cord is broken away in FIG. 2 and omitted from the remaining views for convenience of illustration.

I claim:

The ornamental design for a humidifier, substantially as shown and described.
